UNITED STATES PATENT OFFICE.

JOHN A. DURST, OF PORTLAND, OREGON.

EMERGENCY SAFETY-BRAKE FOR ELEVATORS.

1,303,271.

Specification of Letters Patent. Patented May 13, 1919.

Application filed October 27, 1916, Serial No. 128,088. Renewed March 7, 1919. Serial No. 281,291.

To all whom it may concern:

Be it known that I, JOHN A. DURST, a citizen of the United States, residing at Portland, in the county of Multnomah and State 5 of Oregon, have invented certain new and useful Improvements in Emergency Safety-Brakes for Elevators, of which the following is a specification.

This invention relates to an improvement 10 in safety brakes for elevators, and more particularly to an emergency brake adapted to be fitted in conjunction with an elevator and so arranged that as the elevator is operating under normal conditions this brake mechanism is at all times held in an inoperative 15 position but as the hoisting cable or chain may break or is suddenly released, the brake will become operative to stop the falling movement of the car or lift and will maintain the same against dropping to the bottom 20 of the shaft.

An object of my invention is to provide a 25 brake means of the type described which is so arranged that by itself it is not capable of setting to a braking position, and to arrange means along the wall of the shaft in such a manner that as the car may be momentarily released from its suspension by the cable through slipping of the same or is 30 permanently released through breaking of the cable or breaking of some of the parts of the cable drum operating mechanism, the brake means will be gradually set and will thus bring the car or lift to a gradual though 35 positive stop.

A further object is to provide means arranged in conjunction with the hoisting cable or chain attaching means for the car or lift that as the car or lift is suspended 40 through the medium of this cable or chain the brake means is rendered inoperative, and as raising tension is exerted upon the cable or chain attaching means following the locking of the brake, the brake may then be manually released through movement of the 45 brake setting means.

With the above and other objects in view, my invention consists in certain novel features of construction and combinations of 50 parts which will be hereinafter set forth in connection with the drawings and then more particularly pointed out in the claims.

In the drawings:

Figure 1 is a view taken transversely and 55 horizontally through the elevator shaft and

looking down upon the top of the elevator car.

Fig. 2 is a sectional view of the upper portion of the car having the brake mechanism mounted thereon and which section is 60 taken on the line 2-2 of Fig. 1.

Fig. 3 is a view similar to Fig. 2 but showing the brakes released.

Fig. 4 is a fragmentary detail view taken on the line 4-4 of Fig. 2. 65

Fig. 5 is a detail sectional view of one of the brake shoes.

Fig. 6 is a fragmentary sectional view to show the arrangement of the shoe setting means. 70

Fig. 7 is a fragmentary detail view to show the mounting of the shoe.

The elevator shaft is generally indicated at 1, and the car or lift by the reference character 2, it of course being understood 75 that the shaft and the lift might be of any approved type or of some special form to meet special requirements, these features not forming a part of my invention and therefore not being limited to any particular 80 form. Any suitable form of guideways may be provided to hold the car or lift in the proper path of movement within the shaft, and the hoisting mechanism may be mounted at the top of the shaft or may be placed at 85 the bottom of the shaft and the cable or chain will in this latter connection be extended over a pulley or wheel at the top of the shaft, but in connection with the hoisting means and the mounting of the same, it 90 will be evident that variations might be resorted to without in any manner affecting the successful operation of the device of my invention.

Bearings 3 and 4 are mounted on the top 95 of the car adjacent to the sides thereof and the toggle links 5 and 6 are connected with these bearings and have the rods 7, 8, 9, and 10 mounted therein to be capable of endwise sliding movement, it being understood that 100 a plurality of bearings 3 and toggle links 5 are provided to mount the rods 7 and 8 at one side of the car in such a relation that they are alined, while the rods 9 and 10 are mounted in a similar mounting at the opposite side of the car. These rods 7, 8, 9 and 10 have the brake shoes 11, 12, 13, and 14 carried on the ends thereof and secured in any suitable manner, it being preferable that 105 these shoes be made somewhat after the man- 110

ner shown in Figs. 5 and 7 so that they slide through squared bearings in the upper end of the toggle links by which they are held and it also being preferable that the rods 5 have the ends thereof squared to be received in similarly formed sockets of the brake shoes, the parts being thus so mounted that the rods are held against turning movement. The brake shoes may be secured in place by 10 means of screws as indicated at 15, or in any other suitable way and it is preferable that the outer faces of each of the brake shoes be provided with a roughened surface as shown at 16.

15 A suspending bolt 17 is connected on the top of the car preferably substantially at the center thereof and is made of sufficient size and strength that it will support the entire weight of the car. A yoke 18 is connected 20 around this rod or bolt 17 and is mounted to be capable of free sliding movement along the length thereof, and a coil spring 19 is mounted between the upper side of this yoke 18 and a cap 20 which is mounted on the 25 upper end of the rod or bolt 17 and held in place by the nut 21, or other suitable securing means. A yoke 22 similar to the yoke 18 has the connecting rods 23 and 24 secured at the ends thereof and with the end of the 30 yoke 18, and thus as drawing tension is exerted upon this yoke 22 the pulling strain is exerted against the spring 19. A cable receiving eye 25 is formed as a part of the yoke 22 and the supporting and hoisting cable or 35 chain for the elevator can be connected through this eye. By arranging the parts as has been above set forth, when the cable or chain is connected through the eye 25 and is holding the car in suspension, the spring 19 40 will be compressed sufficiently that the yoke 18 will bear against the lower end of the rim of the cap 20 and consequently the car will be positively held in suspension, but as the tension of the cable or chain may be slackened, 45 or may be released, the springs 19 will expand to move the yoke 18 downwardly to the position shown in Figs. 2 and 4, the opposite extreme position being shown in Fig. 3.

The yoke 18 has the bearing lugs or ears 50 26 extending therefrom on opposite sides and the operating links 27 and 28 are connected with these bearing ears to be capable of swinging movement and at their outer ends are forked as indicated at 29 and 30 so that 55 they will connect with the inner ends of the rods 7, 8, 9 and 10, it however being understood that the rods are arranged to have free sliding movement through the forked ends of the operating links. Brace links 31 and 60 32 are connected with the operating link 27 adjacent to the mounting of the same in conjunction with the yoke 18 and are branched outwardly to have their free ends received around the rods 7 and 8 respectively adjacent 65 to the outer ends thereof, and similar brace

links 33 and 34 are connected with the operating link 28 and are extended to have their spread ends received around the rods 9 and 10, the connection of the brace links being such that the several rods are allowed to have 70 the endwise sliding movement therethrough.

Rack bars 35 and 36 are mounted in any suitable manner to extend vertically along the sides of the elevator shaft and are so positioned that they lie adjacent to the approximate inner ends of the sets of rods 7 and 8, and 9 and 10 respectively. The rods 7 and 8 have oppositely disposed screw threads on the approximate inner ends thereof and a gear wheel 37 which has a somewhat elongated sleeve hub 38 is internally screw threaded, the screw threads at the opposite ends of the bearing sleeve being right and left hand to fit the opposed threads of the rods 7 and 8. A gear wheel 39 which is similar to the gear 80 wheel 37 and is similarly screw threaded, is mounted on the inner end of the rods 9 and 10, which rods are provided with right and left hand screw threads. These gear wheels 37 and 39 are made of such size that as the 85 drawing tension is exerted upon the yoke 18 to raise the same, the operating links 27 and 28 will swing the rods which are carried by the toggle links 5 and 6 sufficiently inwardly that the wheels will be disengaged from the 90 teeth of the rack bars 35 and 36, but as the drawing tension through the eye 25 is released, the spring 19 will force the yoke 18 downwardly and consequently the operating 95 links 27 and 28 together with the brace links 100 connected therewith will cause the various rods to be moved outwardly in a swinging path around the pivotal connection of the toggle links 5 and 6 with the bearings 3 and 4 in consequence of which the gear wheels 37 and 39 will be brought to mesh with the teeth 105 of the racks 35 and 36. As the gear wheels mesh with the teeth of the rack, downward movement of the car will cause these gear 110 wheels to be turned upon the screw threaded inner ends of the rods 7 and 8, and 9 and 10, and as these rods of the two pairs are oppositely screw threaded, the rods 7 and 8 will be extended from their approximate position as will also the rods 9 and 10 and the brake 115 shoes 11, 12, 13 and 14 will be consequently moved outwardly. Wear plates 40, 41, 42, and 43 are connected on the sides of the elevator shaft 1 and are extended vertically in such mounting that as the brake shoes are 120 moved outwardly through the actuation of the mechanism as hereinbefore described, these brake shoes will have their roughened faces as indicated at 16 engaged against the wear plates and consequently a braking action 125 will be accomplished which will increase as the car moves downwardly with the gear wheels 37 and 39 in mesh with the teeth of the rack bars 35 and 36, the pitch of the threads of the various bars being so gaged 130

that the brake shoes will be brought out against the wear plates with a gradual braking pressure and thus the downward movement of the car will be somewhat gradually 5 slowed down and the car will not be brought to a sudden and abrupt stop.

There is of course the possibility that the threads of the various rods having the brake shoes thereon might be stripped or threads 10 within the hubs of the wheels 37 and 39 might be injured in such a way that the parts would not operate upon turning of the gear wheel, and also that other causes might prevent proper operation of the parts, and to 15 guard against such occurrences and against the holding of the brake shoes when they should be set, it is preferable that the springs 44 be fitted around the various rods between the ends of the brace links 31, 32, 33, and 20 34, and the inner ends of the brake shoes 11, 12, 18, and 14 in such relation that as the rods may be free through any cause, these springs will force the brake shoes out against the wear plates and consequently a braking 25 action will be accomplished which will indicate the improper operation of the parts or that portions of the structure are defective.

This locking of the brakes against the wear plates will hold the car not only 30 against downward movement, but also will prevent upward movement of the same even when the cable or chain is again tightened sufficiently to draw the yoke 18 up against the tension of the spring 19 to a degree that 35 the gear wheels 37 and 39 are released from the meshing engagement with the teeth of the rack bars 35 and 36, and therefore it becomes necessary to turn the gear wheels 37 and 39 manually or otherwise to again 40 withdraw the rods 7, 8, 9 and 10 from the extended position in which they bring the brake shoes to the locking engagement against the wear plates. A door 45 is provided in the top of the car and it is thus 45 possible for a mechanic or other person to go up onto the top of the car and make adjustment of a new hoisting cable or chain and after the proper pulling tension is exerted against the spring, to manually turn 50 the gear wheels 37 and 39 to draw the rods back to substantially the relation shown in Fig. 1 where the brake shoes are again set in the inoperative position and are released from all braking action.

55 From the foregoing it will be seen that I have provided an emergency brake for elevator cars which is so constructed and arranged that during proper and normal operation of the elevator the emergency brake 60 means has no effect whatever and the car may be operated and controlled without recourse to such braking means, but immediately the tension of the hoisting cable or chain is slackened as is sometimes occasioned by 65 slipping of the hoisting mechanism or by

breaking of the chain or cable, the brake means will be brought into operation and the emergency brakes will be gradually and then positively set to lock the car against falling movement, the operation of the parts 70 being automatic.

While in the foregoing I have shown and described only one specific form of the invention, it will be understood that a number of changes and variations might be resorted 75 to in the form and arrangement of the several parts of my invention without departing from the spirit and scope thereof, and hence I do not wish to be limited to the exact disclosure but rather only to such points 80 as may be set forth in the claims.

I claim:

1. An emergency safety brake for elevators of the cable hoist type including rods mounted on the elevator car in alinement 85 and having their inner ends oppositely screw-threaded, brake shoes mounted on the outer ends of said rods and located to work against parts of the elevator shaft when the rods are extended, a rack bar mounted on 90 the elevator shaft, a gear wheel having an oppositely threaded internal bore mounted on the threaded ends of said rods, the mounting for said rods being so arranged that movement of the same to throw the 95 gear wheel into and out of mesh with the teeth of the rack bar is permitted, a connection from the hoist to normally hold the rods in such position that the gear wheel is out of mesh with the rack bar, and means 100 to move the parts to an opposite position upon slackening of the hoist cable.

2. An emergency safety brake for elevators of the cable hoist type comprising rods mounted adjacent to the sides of the elevator car, rack bars mounted on the wall of the shaft, said rods screw threaded at their inner ends and provided with brake shoes at their outer ends, gear wheels provided with internally screw threaded hubs 110 mounted on the screw threaded ends of said rods, means with which the cable has connection to normally hold said gear wheels out of mesh with the teeth of the rack bars carried on the sides of the shaft, and means 115 to move said gear wheels into engagement with the teeth of the rack bars upon slackening of the cable to thus cause turning of the gear wheels and consequent extension of the bars to bring the brake shoes thereof into 120 operative position.

3. An emergency safety brake for elevators of the cable hoist type comprising rods mounted adjacent to the sides of the elevator car, rack bars mounted on the wall of the shaft, said rods screw threaded at their inner ends and provided with brake shoes at their outer ends, gear wheels provided with internally screw threaded hubs 125 mounted on the screw threaded ends of said 130

rods, means with which the cable has connection to normally hold said gear wheels out of mesh with the teeth of the rack bars carried on the sides of the shaft, means to 5 move said gear wheels into engagement with the teeth of the rack bars upon slackening of the cable to thus cause turning of the gear wheels and consequent extension of the bars to bring the brake shoes thereof into operative position, and wear plates arranged upon the side of the elevator shaft to have the brake shoes close thereagainst in the braking action.

4. An emergency safety brake for elevators of the cable hoist type comprising a pair of rods for each side of the elevator car, means by which said rods are mounted to be capable of bodily movement toward and away from the sides of the elevator shaft, said rods provided at their outer ends with brake shoes and at their inner ends provided with right and left hand screw threads, gear wheels having the hubs thereof bored and provided with right and left hand screw threads mounted on the threaded ends of the rods, rack bars mounted at the sides of the elevator shaft, operating links connected with the rods to cause movement thereof laterally, a yoke having connection with the operating links and to which the cable has attachment so arranged that as the cable 10 exerts tension against said yoke the rod and gear wheels will be brought inwardly from the sides of the elevator shaft, a spring introduced to exert bearing tension against the yoke in such a manner that as the tension of the cable is slackened the gear wheels will be moved into mesh with the teeth of the rack bars and consequently the rods will be extended from the screw threaded hubs of the gear wheels to bring the brake shoes 15 into operative relation, means by which the movement of the yoke is stopped as the drawing strain of the cable is placed thereon and a positive suspension for the car is accomplished, and means against which the 20 brake shoes work when extended to the braking position.

25 30 35 40

5. An emergency safety brake for elevators of the cable hoist type comprising a pair of rods for each side of the elevator car, means by which said rods are mounted to be capable of bodily movement toward and away from the sides of the elevator shaft, said rods provided at their outer ends with brake shoes and at their inner ends provided with right and left hand screw threads, gear wheels having the hubs thereof bored and provided with right and left hand screw threads mounted on the threaded ends of the rods, rack bars mounted at the sides of the elevator shaft, operating links connected with the rods to cause movement thereof laterally, a yoke having connection with the operating links and to which the cable has attachment so arranged that as the cable exerts tension against said yoke the rod and gear wheels will be brought inwardly from the sides of the elevator shaft, a spring introduced to exert bearing tension against the yoke in such a manner that as the tension of the cable is slackened the gear wheels will be moved into mesh with the teeth of the rack bars and consequently the rods will be extended from the screw threaded hubs of the gear wheels to bring the brake shoes into operative relation.

5. An emergency safety brake for elevators of the cable hoist type comprising a pair of rods for each side of the elevator car, means by which said rods are mounted to be capable of bodily movement toward and away from the sides of the elevator shaft, said rods provided at their outer ends with brake shoes and at their inner ends provided with right and left hand screw threads, gear wheels having the hubs thereof bored and provided with right and left hand screw threads mounted on the threaded ends of the rods, rack bars mounted at the sides of the elevator shaft, operating links connected with the rods to cause movement thereof laterally, a yoke having connection with the operating links and to which the cable has attachment so arranged that as the cable exerts tension against said yoke the rod and gear wheels will be brought inwardly from the sides of the elevator shaft, a spring introduced to exert bearing tension against the yoke in such a manner that as the tension of the cable is slackened the gear wheels will be moved into mesh with the teeth of the rack bars and consequently the rods will be extended from the screw threaded hubs of the gear wheels to bring the brake shoes into operative relation, means by which the movement of the yoke is stopped as the drawing strain of the cable is placed thereon and a positive suspension for the car is accomplished, and means against which the brake shoes work when extended to the braking position.

In testimony whereof I affix my signature in presence of two witnesses.

JOHN A. DURST.
